ROTARY METERING VALVE FOR DIESEL ENGINES

Sanley Lerner, Bronx, N. Y.

Application May 20, 1943, Serial No. 487,823

6 Claims. (Cl. 277—46)

This invention relates to new and useful improvements in a rotary metering valve for Diesel engines.

More specifically, the invention proposes the construction of a rotary metering valve for Diesel engines characterized by a body having one or more fuel discharge ports (one for each cylinder of the engine) starting from a bore in the housing for a slidable and rotative cylindrical valve head designed in a manner to convey equal amounts of fuel from an inlet port successively to each of said discharge ports.

Still further it is proposed to provide the cylindrical valve with a metering groove of a particular shape and alignable with one or more of the discharge ports in various axial shifted positions for controlling the duration of injection in a manner to permit this period of injection to be changed by merely shifting the valve head relative to the housing.

Another object of the invention proposes the provision of passages for connecting the fuel inlet port with metering grooves in all rotative positions of said valve head in a manner to continually supply fuel to said metering groove.

A further object of the invention proposes the provision of a fuel bypass return port connected with the fuel discharge ports by means of a passage and pressure regulating valve arranged in a manner to maintain predetermined residual pressure in a discharge line during the period between injections.

Still another object of the invention proposes the provision of a cut off port for each of the passages connecting the discharge ports with the fuel bypass return port and a land projection on the valve alignable with the cut off ports for closing the cut off port of each fuel discharge port during the time the metering groove is aligned with the discharge port to prevent the fuel being supplied to the discharge port under pressure from escaping through the fuel bypass return port.

It is further proposed to construct the land projection to coincide with the shape and size of the metering groove but slightly wider to keep the cut off port closed for a period before and after the metering groove uncovers the respective discharge port in a manner to prevent the pressure in the line from the pressure pump from dropping before and after the injection.

It is still another object of this invention to construct a rotary metering valve for a Diesel engine which is inherently, much less intricate in

design, less costly to manufacture and requires less material and work since only one metering valve is normally required for the entire engine.

For further comprehension of the invention, and of the objects and advantages thereof, reference will be had to the following description and accompanying drawing, and to the appended claims in which the various novel features of the invention are more particularly set forth.

10 In the accompanying drawing forming a material part of this disclosure:

Fig. 1 is a longitudinal sectional view of a rotary metering valve for Diesel engines constructed in accordance with this invention.

15 Fig. 2 is a sectional view taken on the line 2—2 of Fig. 1.

Fig. 3 is a vertical sectional view of the line 3—3 of Fig. 1.

20 Fig. 4 is a vertical sectional view on the line 4—4 of Fig. 1.

Fig. 5 is a vertical sectional view of pressure regulating valve of the bypass return port.

25 Fig. 6 is a view similar to Fig. 1 but illustrating a modification of the invention.

Fig. 7 is a horizontal sectional view taken on the line 7—7 of Fig. 6.

The rotary metering valve for Diesel engines, according to this invention, includes a body 10 having one or more fuel discharge ports 11 starting from a bore 12 in the body 10 and radiating therefrom. On the drawing, only two discharge ports are shown, but it is to be understood that this is by way of illustration only, and that in actual practice there will be one discharge port 11 for each of the cylinders of the Diesel engine. That is: If the engine has six cylinders there will be six discharge ports in the housing 10.

30 The bore 12 of the housing carries a slidable and rotative cylindrical valve head 13 which cuts off the entrance to the discharge ports 11. The valve head 13 is adapted to be rotated by an external source of power (not shown on the drawing) and properly timed to the engine and its axial slidable movement is controlled by a governor (not shown on the drawing) for a purpose which will hereinafter become clear as this specification proceeds. Details of the rotating and sliding mechanism are not shown on the drawing as they form no part of this invention and such devices are generally known to those skilled in the art.

35 The valve head 13 is formed with a metering groove 14 which is wider at one end than the other and arranged to be aligned with one or more of the discharge ports 11 during rotation of

the valve head 13. Shifting the valve head longitudinally will align different lateral widths of the metering groove 14 with the discharge ports 11. Since the metering groove 14 is of different widths throughout, this shifting will control the length of the duration of injection.

The body 10 is formed with a fuel inlet port 15 which is adapted to be connected with a pressure pump (not shown on the drawing) for supplying fuel oil under pressure. Passages connect the metering groove 14 with the fuel inlet port 15 in all positions of the valve head for continually supplying fuel under pressure to the metering groove 14. These passages are characterized by an opening 16 which extends from the inlet port 15 to the bore 12. The opening 16 is aligned, in all shifted positions of the valve head 13 connected with a circular groove 17 formed in the valve head 13 adjacent the metering groove 14.

The circular groove 17 is in turn connected with the metering groove 14 by an angular opening 18 extended through the valve head 13 from the circular groove 17 to the metering groove 14.

The body 10 is also formed with a fuel bypass return port 19 which is connected with each of the one or more fuel discharge ports 11 by passages. These latter passages are characterized by branch passages 20 extending from an intermediate portion of the discharge ports 11 to the bore 12. These branch passages 20 are aligned in all shifted positions of the valve head 13 with a circular groove 21 formed in the valve head 13. A passage 22 then connects the groove 21, in all shifted positions of the valve head 13, with the fuel bypass return port 19.

The fuel bypass return port 19 is connected with the inlet to the pressure pump (not shown on the drawing) or returned to the fuel tank by a pipe 23. Arranged in conjunction with the bypass return port 19, and more specifically in an intermediate portion of the pipe 23, there is a pressure regulating valve 24 for regulating the pressure in the fuel discharge ports 11 during the time that no injection is taking place.

The pressure regulating valve 24 is characterized by a housing 25 mounted in the housing 10 and formed with an internal valve seat 26. A screw 27 threadedly engages the housing 25 at a point opposite the valve seat 26. A valve member 28 is engageable upon the seat 26 and has a stem 29 projecting therefrom and which slidably engages into an opening 30 formed in the inner end of the screw 27. An expansion spring 31 is coaxially engaged upon the stem 29 and bears between opposite faces of the valve member 28 and the inner end of the screw 27 to urge the valve member 28 into a seated position on the valve seat 26 to close the passage through the pipe 23.

Adjustments made to the screw 27 will control the pressure exerted by the spring 31 in seating the valve member 28 upon the valve seat 26. A nut 32 threadedly engages the screw 27 and is arranged to be tightened against the body 25 for holding the screw 27 in any desired adjusted position.

A land projection 33 is formed on the valve head 13. This land projection 33 is formed on the valve head 13 in an aligned position with the metering groove 14 and is of a similar shape, that is, smaller at one end than the other. However, this land projection is of a size slightly greater than the metering groove 14.

Each of the passages which connects the fuel discharge ports 11 with the fuel bypass return

port 19 is formed with a cut off port 34. These cut off ports 34 are located in the branch passages 20 at the point where these passages 20 contact the bore 12. With this construction the land projection 33 is alignable with the cut off ports 34 during the rotation of the valve head 13 and in all shifted positions thereof. Thus, the land projection 33 will close the cut off port 34 of each fuel discharge port 11 approximately during the time that the metering groove 14 supplies each of the discharge ports 11 with fuel during the injection period. Making the land projection 33 larger than the metering groove 14 insures closing of the cut off port 34 a fraction of a second before the injection period starts and opening of the cut off port 34 a fraction of a second after the injection period stops to prevent the pressure in the line from the pressure pump from dropping before and after the injection period.

The operation of this invention is as follows:

Fuel from the pressure pump enters the inlet port 15 and proceeds to the metering groove 14 through the passages 16, 17 and 18. Injection begins when the metering groove 14 uncovers the discharge port 11 as the land projection covers the cut off port 34 of the particular discharge port 11 which has been uncovered.

The duration of the injection period is controlled by the lateral width of the metering groove 14 which is aligned with the entrance to the discharge port 11. Aligning different portions of the metering groove 14 with the discharge ports is controlled by shifting the valve head relative to the body 10.

Injection stops when the discharge port 11 is again closed and the land projection 33 moves clear of the cut off port 34 opening the port. Pressure within the discharge port 11 is maintained by the valve 24. If the pressure in the discharge 11 is greater than the pressure for which the valve 24 is provided, this pressure will back up through the fuel bypass return port 19 and unseat the valve member 28 permitting this additional pressure to pass through the pipe 23 back to the inlet to the pressure pump.

In the modification of the invention shown in Figs. 6 and 7, the construction of the rotary metering valve for Diesel engines is similar to that previously described, except for the means for connecting the circular groove 17 in the valve head 13 with the metering groove 14.

In this form of the invention, this connecting means is characterized by a groove 18' formed in the face of the valve head 13 between the circular groove 17 and the metering groove 14.

In other respects this form of the invention is similar to that previously shown and like reference numerals identify like parts in each of the several views.

This device may also be constructed with the metering groove and cut off land projection in the bore of the housing instead of in the valve head.

The device is not limited to use in Diesel engines. It may be used wherever equal quantities of liquid or gas, to any mechanism is desired.

It may also be used without pressure regulating valve, if so desired, or individual check valves may also be employed in each discharge line.

The valve may seal leakage in the housing by accurately fitted parts or conventional high pressure packing glands.

While I have illustrated and described the preferred embodiments of my invention, it is to be

understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel by-pass return port, passages connecting each of said one or more fuel discharge ports with said fuel by-pass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports.

2. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel by-pass return port, passages connecting each of said one or more fuel discharge ports with said fuel by-pass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports, said metering groove being wider at one end than the other for controlling the amount of fuel that will be delivered to the discharge ports

as the valve head is shifted longitudinally relative to the body.

3. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel by-pass return port, passages connecting each of said one or more fuel discharge ports with said fuel by-pass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports, said first mentioned passages comprising an opening leading from said inlet port through said body to said bore, a circular groove formed in said valve head and communicating with said opening in all shifted positions of said valve head, and means connecting said circular groove with said metering groove.

4. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel by-pass return port, passages connecting each of said one or more fuel discharge ports with said fuel by-pass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports, said first mentioned passages comprising an opening leading from said inlet port through said body to said bore, a circular groove formed in said valve head and communicating with said opening in all

shifted positions of said valve head, and means connecting said circular groove with said metering groove, said latter means, comprising an annular opening extended through said valve head from said circular groove to said metering groove.

5. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel by-pass return port, passages connecting each of said one or more fuel discharge ports with said fuel bypass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports, said cut-off ports comprising branch passages connecting each of said discharge ports with said bore, a circular groove formed in said valve head and connecting with said branch pas-

sages in all shifted positions of said valve head and during the time that said land projection is disaligned therewith, and a passage in said body connecting said circular groove with said bypass return port.

6. A rotary metering valve for Diesel engines, comprising a body having one or more radially disposed fuel discharge ports starting from a bore therein for a slidable and rotative cylindrical valve head, a slidable and rotative cylindrical valve head within said body and cutting off said discharge ports, said valve head having a metering groove alignable separately with said one or more fuel discharge ports during its rotation, said metering groove being longer than the diameter of said discharge ports and having its length extended parallel to the length of said cylindrical valve head, said body having a fuel inlet port, passages connecting said fuel inlet port with said metering groove in all positions of said valve head, said body having a fuel bypass return port, passages connecting each of said one or more fuel discharge ports with said fuel bypass return port and including a cut off port for each of said one or more fuel discharge ports, and a land projection on said valve head and of similar shape and approximate size to said metering groove and alignable separately with said cut off ports while said metering groove is aligned separately with the corresponding of said discharge ports, whereby when said valve head is slid relative to said body to align a different area of said metering groove with said discharge ports, said land projection will be similarly moved to align a complementary portion of said land projection with the corresponding of said cut off ports, and a pressure regulating valve in said bypass return port.
